UNITED STATES PATENT OFFICE.

WALTER THOMAS AND ALBERT E. MAINWARING, OF NANAIMO, BRITISH COLUMBIA,
CANADA.

PROCESS OF GENERATING HEAT.

1,221,627.

Specification of Letters Patent.

Patented Apr. 3, 1917.

Original application filed July 9, 1914, Serial No. 849,924. Divided and this application filed September 17, 1914, Serial No. 862,238. Renewed December 14, 1916. Serial No. 137,508.

To all whom it may concern:

Be it known that we, WALTER THOMAS and ALBERT E. MAINWARING, subjects of the King of Great Britain, residing at Nanaimo, in the county of Nanaimo and Province of British Columbia, Canada, have invented certain new and useful Improvements in Processes of Generating Heat, of which the following is a specification.

10 This invention relates to a process of generating heat from low-grade fuel for heating all classes of steam boilers, and for other industrial purposes, such as heating bakery ovens, brick and pottery kilns, ore 15 roasting furnaces, lime and cement kilns or retorts, etc., in an economical and scientific manner.

At the present time there are large quantities of low-grade fuel, such as mine waste 20 or refuse, lignite, and lignite coal, wood waste and other waste material in most parts of the world, which is not successfully utilized for heating purposes, for the reason that the processes and furnaces in general 25 use are not adapted for generating high and uniform heat from such classes of fuel. There are large quantities of cheap, low-grade fuel in Canada and the United States which is not used for heating purposes by 30 reason of the lack of a suitable process and generator to consume it, to gasify it, burn the hydrocarbon gases, produce perfect combustion, and develop the highest possible calorific value.

35 We have devised a process which overcomes the difficulties heretofore encountered in burning low-grade fuel, and which will produce the beneficial and advantageous results above mentioned in a thoroughly practical and scientific manner. By our process 40 we will absolutely do away with the smoke nuisance and at the same time effectively utilize the cheap, low-grade fuels, as we have conclusively demonstrated by months 45 of practical operation in our heat generating furnace.

The general object of our invention, therefore, is to generate high heat under perfect control, from low-grade fuels, by wholly or 50 partially coking the fuel, liberating the rich hydrocarbon gases, completely burning such gases with air, producing perfect combus-

tion, also burning the coked fuel and maintaining a regulated temperature at any desired degree.

One of the special objects of our invention is to provide for coking and gasifying low-grade fuel and producing two rates of combustion at variable but controlled temperatures,—one a comparatively rapid combustion of the gases at a high temperature, and a slower combustion of the fuel at a lower temperature, whereby any desired heat or temperature may be obtained, best suited to the work to be accomplished.

Another object is to provide a process for subjecting coal or a low-grade fuel to a coking operation, thereby liberating hydrocarbon gases and vapors and injecting the same with air or steam and air, into a body of 70 ignited or incandescent coked fuel, whereby the rich hydrocarbon vapors are converted into fixed gas, composed principally of hydrogen, light carbureted hydrogen and carbon monoxid; burning such gases with secondary air in a combustion zone,—producing perfect combustion and the highest possible efficiency.

Both the primary and the secondary combustion in our process and generator are under perfect control, so that the exact temperature required may be obtained. Other objects and purposes of our invention will appear in the detail description of the apparatus and its operation below.

The matter constituting our invention will be defined in the claims.

We will now describe our process by reference to the accompanying drawings, in which—

Figure 1, represents a longitudinal section, with parts in elevation of one form of furnace adapted for carrying out our process, and showing a tubular steam boiler mounted thereon.

Fig. 2, represents a horizontal section through the furnace on the irregular line 2—2, Fig. 1.

Fig. 3, represents a sectional detail on enlarged scale, showing a Bunsen injector on 100 a hollow grate bar.

Fig. 4, represents a detail view of a modified construction of grate bar showing a Bunsen injector.

Fig. 6, represents a longitudinal section of a modified construction of a boiler furnace on line 6—6, Fig. 7.

Fig. 7, represents a transverse section of the same on line 7—7, Fig. 6.

Fig. 8, represents a longitudinal section of a modified arrangement of heat generating furnace.

Fig. 9, represents a transverse section showing modifications.

We construct the walls of our heat generating furnace 1, of brick and may line it 15 with fire brick, and erect on a concrete foundation X, and with an upwardly inclined top 1^a, to provide a heating chamber for the inclined coking retort. The furnace 1, Figs. 1 and 2, is provided with a fuel and 20 primary combustion chamber 2, a grate composed of hollow bars 3 and 22 resting on cross bars 4^a, and an ash pit 4. The chamber 2, is provided with a front opening and door 5, for clinkering and stoking the bed 25 of fuel, and chamber 4 is provided with an ash door 6. The coking and fuel feeding retort 7, may be set in an inclined position as shown in Fig. 1, or in a vertical or horizontal position, and is provided with a 30 mouth piece 8, having a tight fitting lid or door 9, constructed in any well known manner. The retort is supported in a combustion chamber 10^a, so that it may be subjected to a high temperature for coking the 35 coal or other low-grade fuel and liberating rich volatile hydrocarbon gases and vapors. A combustion chamber 10, of comparatively large capacity is provided above the body of fuel on the grate for the secondary and 40 complete combustion of gases.

At one end of the furnace is seated a vertical tubular boiler 12, having a stack 12^a, a steam pressure gage 11, a safety valve 11^a, and a water gage 11^b. An outlet pipe 13, 45 having a valve *g*, may connect with the combustion chamber 10^a, for conducting off hot gaseous products to any desired place of use.

We wish it understood that instead of 50 mounting a steam boiler on our heat generator, a baking or roasting oven, or a kiln or other device to be heated may be located at the rear of the generator or connected therewith in any suitable manner for most effectively utilizing the large volume of highly 55 heated products generated.

A positive air blower 14, of any well known kind, and having an air inlet *k*, is mounted in any convenient position, and 60 has an air blast discharge pipe 17, with which connects a pipe 15, having a valve *a*, leading to a secondary air heating coil 16, located in the top of the boiler or in any flue or conduit for hot gases, whereby it may 65 be heated. The air blast pipe 17, terminates

with a nozzle 17^a, Fig. 5, in the injector 18, to act as an exhauster for drawing gas and vapor from retort 7 through pipe 20 connecting with the mouth-piece 8, as shown. At the outlet of the injector, a pipe 19, 70 is extended to the hollow grate bars 3. Pipe 19, will therefore conduct mixed gas and high pressure air to part of the hollow grate bars, particularly to those marked 3. A second branch pipe 21, having a valve *c*, connects with pipe 17, and leads to the side hollow grate bars 22, in the furnace.

Any desired number of Bunsen injectors 25, will be connected in the grate bars 3, and 22. To form an injector, a nipple 26, 80 Fig. 3, may be screwed into the top of the pipe or bar 3, and is inclosed in an injector bell 27, which is held in place by a spider, or in other desired manner. The construction of grate bar and injector may 85 be modified as shown in Fig. 4, in which is shown a solid grate bar 28, having conical openings 29. A pipe 23, for air blast or mixed air and gas is arranged below bar 28, and is provided with a nipple or nozzle 24, 90 projecting up into the conical opening 29, for producing a Bunsen burner flame. These Bunsen injectors will draw air or air and water vapor from the ash pit and mix it with the gas or gas and air and force it 95 up into the body of ignited or incandescent fuel. The Bunsen injectors 25, on the air bars 22, will also draw additional air or steam from the ash pit and force it up into the body of fuel, producing a forced draft 100 and rapid combustion, particularly of the rich gases and vapors supplied by pipe 3.

Gas alone may be drawn from the retort 7 and forced into the hollow bars 3 and thence through the injector burners 25 for 105 drawing in air or steam and air and supplying the mixture to the ignited fuel, as indicated by the construction shown in Fig. 9.

A hot air pipe 30, having a valve *d*, connects with the air heating coil 16, at the top 110 of the boiler and with the secondary air ducts 31, in the side walls, which ducts have numerous ports 32, opening into the secondary combustion chamber 10, above the fuel. A branch pipe 35, having a valve *e*, connects 115 with pipe 19, and leads into the duct 31, or connects by a pipe 36, having a valve *h*, with air pipe 30, at the rear end of the furnace, so that the mixed gas and air blast can be passed with hot air from pipe 30, 120 into the secondary air ducts 31. We have found it advantageous in some conditions to thus burn all or part of the rich hydrocarbon gas in chamber 10, above the body of fuel. Evidently part of the gas may be 125 burned in the Bunsen injectors at the grate and part in chamber 10, above the solid fuel, according to the character of the gas and other conditions present.

A water supply pipe 33, having a valve *f*, 130

connects with the ash pit and supplies it with water to be vaporized. By means of the Bunsen injectors steam is forced into the incandescent fuel where it is decomposed into hydrogen and carbon monoxid, thereby adding to the supply of combustible gas in the secondary combustion chamber.

The arrangement of coking retorts 7^a, shown in Figs. 6 and 7, is particularly adapted for some forms of steam boiler furnaces, and other large furnaces, in which a deep fuel bed is preferably maintained in chamber 2. The retorts 7^a may be supported on shelves or brackets at each side 10 of the furnace and partially surrounded with flues 10^b for hot products, and are each provided with a bottom opening 7^b having a slide 7^c for discharge of coke into the combustion chamber. The construction of the 20 other parts may be substantially as before described.

In case a small, inexpensive installation is desired, the coking chamber 7^c and fuel chamber 2^a, Fig. 8, are made in single 25 in-closing walls and separated by a partition 40, having an opening 41, connecting the chambers, whereby hot coke may be pushed from the coking chamber back into the combustion chamber. One Bunsen burner 25 on 30 an air pipe 22 may open into the coking chamber for supporting a low or smothered combustion, suitable for coking or charring the fuel. The chamber 2^a will be provided with hollow bars and injector burners for 35 gas and air as above described. The hot products may be passed off through a flue 10^d to any desired place of use. A steam-jet exhauster and air blower 18^a may be used with this form of heat generator; also 40 with any construction of our generator, as a substitute for the air blower 14.

The coking retort may have an enlargement 7^d, to provide a gas receiving chamber when the retort is opened for feeding 45 or discharging fuel. A rotary gas exhauster 18^b may be connected in the gas outlet pipe 20, instead of an air or steam jet exhauster previously described. Air inlet pipes 21^a may be placed in, or connected with, the retort or chamber 7 for supplying the requisite 50 amount of air to hasten the coking operation. Gas drawn by the exhauster 18^b may be forced directly into the hollow bars 3, and thence through the injector burners, 55 thereby drawing in air or steam and injecting it into the body of incandescent fuel in chamber 2, where complete combustion is effected and a high heat produced.

The operation of our heat generator is 60 very simple and may be conducted as follows: A body of fuel is placed on the grate and ignited, and the coking retort charged with coal or waste fuel. The air blower may be started and an air blast supplied to 65 the hollow grate bars. As the temperature

rises in the furnace, the fuel in the retort will be coked or charred and hydrocarbon gases evolved. High pressure air will now be admitted to the injector 18, which will draw the gas and vapor from the retort and force them with air into the Bunsen injectors 25, and thence into the incandescent fuel where primary combustion is wholly or partially effected. Steam will also be drawn into the injectors and discharged 70 into the fuel where it will be decomposed. All the gases will be broken up to form hydrogen, light carbureted hydrogen and carbon monoxid. The volume of gas will be largely increased and the hot gas passing 75 through the body of the fuel will be met by, and intimately mixed with the secondary hot air from the ports 32, resulting in perfect combustion in chambers 10 and 10^a, around the coking retort. The so-called 80 smoke will be completely consumed and the smoke nuisance thus overcome. The coke will, at suitable intervals, be pushed down into chamber 2, and fresh fuel supplied to the retort in any desired manner. The body 85 of fuel in chamber 2, will be regulated and stoked by bars through the door 5. The ashes will be removed as required through door 6. A shallow body of water will be maintained in the ash pit to supply steam 90 as above described.

Two different rates of combustion may be established and maintained, first the slower combustion of the fuel supplied with air from the hollow grates 22, producing a 100 comparatively low temperature; and second, a more rapid combustion of the gases with air, producing a higher temperature. Both of these rates of combustion will be controlled by controlling the air and gas 105 admitted to the combustion chambers. Any desired heats or temperatures can thus be produced and maintained as may be best suited to the work to be performed.

The high efficiency of our generator is 110 largely effected by the operation of breaking up the heavy hydrocarbons, generated in the retort, by the operation of forcing the gases, vapors and air directly into certain areas of the incandescent fuel, as by 115 means of the Bunsen injectors. This we have found much more effective than supplying air under pressure under the whole grate area, which latter we have found absolutely unsuitable for burning low-grade 120 fuel. By use of a suitable number of Bunsen injectors and air under pressure, clinker is formed in cone shaped chunks around and over each injector and can be easily removed without withdrawing the fire or lowering 125 the temperature of the generator.

The apparatus herein shown and described is made the subject of our copending application, Serial Number 849924, filed July 9, 1914.

Having described our invention, what we claim and desire to secure by Letters Patent, is:—

1. In the generation of heat, the process which consists in coking or charring a separate body of fuel and liberating the rich hydrocarbon vapors and gases, and drawing off such vapors and gases and mixing them with air and forcing the mixture in jets at localized points directly into a body of incandescent coked fuel, thereby decomposing the mixture into fixed gases, mixing air therewith and producing perfect combustion, whereby low-grade fuel may be used and a high heat obtained.
2. In the generation of heat, the process which consists in generating or liberating hydrocarbon vapors and gases from a body of fuel, drawing off such vapors and gases by a blast of high pressure air, and passing the mixture in jets at localized points into a body of incandescent fuel, thereby producing perfect combustion of the fuel and gases and causing the earthy and mineral matter to be reduced to separate masses of clinker.
3. In the generation of heat, the process which consists in coking or charring a separate body of fuel and generating hydrocarbon vapors and gases, burning the resulting coke to form a body of incandescent fuel, drawing off the hydrocarbon vapors and gases by a blast of high pressure air from the first body of fuel and forcing them

in jets partly above, and partly into, the body of incandescent fuel, thereby producing perfect combustion of the fuel and gases.

4. The process of generating heat which consists in charring or coking a separate body of fuel, and generating hydrocarbon vapors and gases, drawing off and injecting such vapors and gases in separate jets at localized points directly into a body of highly heated or incandescent fuel resulting from the previous charring or coking operation, and into a combustion chamber above the fuel and supplying air thereto for causing complete combustion, whereby low-grade fuel may be utilized and perfect combustion produced.

5. In the generation of heat, the process which consists in generating or liberating hydrocarbon vapors and gases from a separate body of fuel, drawing off such vapors and gases by a blast of high pressure air, and forcing the mixture in streams into a combustion chamber above the body of incandescent fuel, thereby producing perfect combustion of the fuel and gases.

In testimony whereof we affix our signatures in presence of two witnesses.

WALTER THOMAS.
ALBERT E. MAINWARING.
